UNITED STATES PATENT OFFICE.

EDWARD JONES, OF LEAVENWORTH, KANSAS.

REVETMENT.

1,407,866.

Specification of Letters Patent. Patented Feb. 28, 1922.

Application filed December 27, 1920. Serial No. 433,235.

To all whom it may concern:

Be it known that I, EDWARD JONES, a citizen of the United States, residing at Leavenworth, in the county of Leavenworth 5 and State of Kansas, have invented certain new and useful Improvements in Revetment, of which the following is a specification.

My invention relates to revetment for the protection of river banks, river beds, shores, dikes and the like, from the destructive actions of water, and to the method of constructing the same, and, is a distinct and practical improvement to overcome certain 15 serious and important practical objections to, and defects in, past and present forms, styles and structures of revetment and method of constructing same.

An important object of my invention is 20 to provide the river bed adjoining the river bank, or slope with a coating of quarry spalls, crushed stone, gravel, or equivalent material, graded in size from fine to the largest fragment, so that it will result in 25 the least percentage of voids. This coating is to preferably cover the entire area that is to be later covered by what is known as a foot mattress.

A further object is to provide a foot mat- 30 tress made from a sound bar growth of willows, of suitable diameters and lengths, the stitch being over and under and made in such a manner that deep pockets shall be formed between the stitches for the re- 35 ception of ballast retainers in the form of suitable size quarry spalls, or their equivalent.

A still further object of the invention is 40 to strengthen the mattress with a system of crossed metallic strands laid in engagement with the bottom face of the foot mattress, and, at intervals to be pulled up to the top surface of the mattress and provided with wooden toggles shoved under the bites 45 formed in the strands to twist the crossing strands and finally wiring both ends of the toggles to the foot mattress.

A still further object of the invention is 50 to provide the upper face of the mattress with a layer of graded quarry spalls, gravel, crushed stone, or its equivalent.

A still further object of the invention is the provision of a revetment, and method of constructing the same, that will guard

against the possible scour which usually 55 takes place within the area of the river bed covered by the foot mattress.

A still further object of the invention is the provision of a revetment which may be successfully used in connection with a dike 60 structure for protecting the dike from undue scour of the river bed, which scour causes an undermining which reduces penetration of dike piles, weakening same and allowing foot mattress to settle. 65

Other objects and advantages of the invention will be apparent during the course of the following specification, and, what the invention consists in is more particularly set forth hereinafter and finally pointed out in 70 the claims hereto appended.

Referring to the accompanying drawings forming a part of this specification wherein like characters of reference denote similar parts throughout the several views: 75

Fig. 1, is a plan view of my improved revetment with portions thereof removed to clearly show the structure thereof.

Fig. 2, is a side elevation thereof.

Fig. 3, is a plan view of the revetment 80 used in connection with a dike.

Fig. 4, is a side elevation thereof.

Fig. 5, is a detail, in sectional elevation, of a portion of the revetment.

Referring, now, to the accompanying 85 drawings, that part of the river bank designated 1 shall be referred to as the lower bank, or river bed; and, that part designated 2 shall be referred to as the upper bank, or shore. 90

In carrying out the aim of my invention where the revetment is used for protecting river banks remote from dikes, the upper bank 2 is first suitably graded with a view to forming a suitable continuous slope from 95 its top to the river bed, or lower bank 1, and the cross section thereof shall be sufficiently close together to determine the amount of earth necessary to be cut from the upper bank 2 to form a suitable slope 100 from the water's edge to the river bed on the lower bank to avoid any bluff bank below the water. The slope of the upper bank 2 is determined by the quality of earth necessary to make the opposite fill, and, in 105 no case should a bluff bank be permitted to exist or remain in the lower bank 1 to be later covered with revetment, even though

other material has been deposited to aid in securing a continuous slope to the river bed. No attempt should be made to degrade projecting points as the excess earth causes a 5 fill and accentuates the trouble. Where holes are made in the slope due to hydraulic grading, or from rain or wave wash, they should be filled with earth, sand or equivalent material. Upon completion of this 10 operation, both the lower bank 2 and the upper bank 1 should present a fairly even surface to receive a suitable graded quarry spall, or crushed stone coating, or the equivalent thereof, as will be hereinafter more 15 fully set forth.

In advance of foot mattress weaving and following close behind the grading operations, the lower bank 2, or river bed and a suitable area of the upper bank 1 above the 20 water edge, is provided with a coating of suitable thickness, for example six inches thick, although not limited to such dimensions, of graded quarry spalls, crushed stone, gravel, or equivalent material designated 25 3, graded in size from the finest fragment to the largest fragment so as to provide a suitable and substantial bed foundation, or base coating laid upon the lower bank 2, which coating will result in the 30 least number of voids. The coating 3 is spread over the lower bank 2 of the river bed to be later covered with a suitable foot mattress, which will now be described.

Referring, now, to the foot mattress, 35 designated 4. This mattress is, for example, although not limited to such dimensions, approximately twelve inches thick and of a minimum width of approximately eighty six feet, the length thereof being determined by conditions.

The shore edge designated 5 of the mattress 4, should lie, although not limited to such dimensions, approximately three feet above the standard low water line designated 45 6 when work is carried on, but it may be placed as high above the standard levels, as desired, depending usually upon the river stages at time of work. The foot mattress may be increased in width when working 50 above three foot stage so that the mattress may extend any suitable distance out from the standard low water stage line with the upper bank 1.

The foot mattress designated 4, which I 55 employ, is made from sound bar growth willows designated 7. These willows preferably range from one inch to four inches in diameter at the butt ends and from twelve to twenty five feet long, although I do not 60 wish to be understood as limiting myself to such dimensions. The stitch of the willows in forming the mattress is over and under, to form deep pockets between the stitches, which pockets act in the capacity 65 of retainers of a suitable graded crushed

quarry spall ballast 7'. A smooth close woven mat made of smaller willows has been found, in years of practice, to be impractical and worthless, as such a mattress will not retain the necessary ballast to carry out 70 the aim of my invention. My object is to fill all of the pockets, reticulations or crevices formed in the mattress with suitable graded ballast causing the mattress and ballast to form close contact with the lower 75 bank coating or foundation 3 and to act as a substantial proof or floor against scour.

A suitable layer or coating 8 of preferably graded quarry spalls, crushed stone, or 80 its equivalent, and of the same quality as the mattress ballast material is spread over the entire top of the foot mattress to cover and protect the mattress and its ballast, as is manifest.

Prior to filling the pockets of the foot mattress with suitable ballast material, I strengthen the foot mattress 4 by a system of suitable metallic strands. The mattress strengthening system consists of a plurality 90 of longitudinal strands 9 spaced a suitable distance apart and a plurality of transverse strands 10. These strands 9 and 10 are laid in contact with the bottom face of the mattress 4. At the intersections of the longitudinal and transverse strands 9 and 10, they are pulled up to form an inverted U-shaped bite 11 extending upwardly a suitable distance above the top surface of the mattress and cross each other at right angles, as is 95 manifest.

Wooden toggles 12 are employed, and these toggles are, for example, six inches in diameter and four feet long, although not limited to these dimensions. The toggles are shoved under the crossed bites formed by the strands, and, the toggles are given a round turn to twist the strand bites, the toggle acting as a lever, as is manifest. Both ends of the toggles are preferably 110 wired or otherwise suitably fixed to the willows of the mattress 4 to prevent displacement thereof. These toggles assist to hold the willows together in the form of a foot mattress and further act as baffles to retain 115 the rock covering upon the mattress and prevent displacement thereof, as is manifest.

Briefly speaking, it is evident from the foregoing description, that the revetment 120 consists of a layer of graded quarry spalls, or its equivalent to provide a base, a willow foot mattress formed with deep pockets to retain a suitable quarry spall ballast, and finally a top coating of suitably graded 125 quarry ballast, the whole forming a body substantially free from voids and providing a revetment which will eliminate the scour and erosion which is the chief cause of revetment destruction. Where scour of the 130

river bed or lower bank is eliminated, permanent revetment is assured.

The foregoing description has referred to the use of the revetment as a protection to river banks, shores, and the like and the following will refer to the use of my improved revetment in connection with a dike, which structures are used on alluvial rivers for diverting and concentrating channels, closing side chutes, and the like.

Referring to Figures 4 and 5 of the drawings, I have illustrated a clump type of dike. The dike consists of a plurality of rows of piling arranged in clumps, or groups designated A with three pilings to a clump. The heads of the piling comprising each clump, are pulled together and lashed with a metallic strand B. A rider C consisting of long piling is dropped between the two rows of clumps to strengthen the dike transversely. A suitable crib C extends from the shore end of the dike and consists of brush c and suitable stone c' intermingled, as shown in Figures 4 and 5. The stone c' may be graded, if desired.

The failure of dikes to carry out their intended purpose is usually due to scour. A proof that the failure is usually due to scour, is that the foot mattress settles until the penetration of the piling over a certain area is so reduced that overturning of the piles from weight above is the natural result and no amount of cables, packing blocks, or double bracing will change the result. Soundings taken across a breached section of dikes confirms the conclusion that the foot mattress settlement is the direct cause of the largest per cent of dike failures, thus it is clear that the foot mattress of dikes, as now used and applied, certainly do not prevent scour and settlement of mattress that may result in disaster to an entire project.

To overcome these dike failures, I employ the same revetment structure previously described, namely, a graded quarry spall foundation laid upon the river bed, or lower bank 2 and I lay thereupon the woven willow mattress 4. This mattress has the greatest possibilities for making a scour proof footing 50 that will stabilize dike structures in that the foot mattress for dike structures is preferably constructed with the brush top on the under side of the mat so as to press down and hold in place the foundation of scour 55 proof material preventing any loss thereof by displacement. The pockets formed in the woven mat being filled with the suitable scour proof ballast 7', it will be in order to view my improved revetment from an 60 entirely different point than the ordinary well known woven willow mat, for instead of depending on the mat to act alone as the foundation for a dike, it will assume a secondary place, namely, a retainer for a material that is scour proof which, in turn, is

laid upon a graded quarry spall foundation, which is also scour proof, thereby eliminating the possibilities of mat settling adjacent to the base of the dike piles, as scour of the river bed thereunder is practically impossible.

Most any style of dike would probably withstand against the forces for which they were designed, providing that the conditions surrounding them remained stationary, but, immediately upon completion of a dike, the conditions become very much altered, the area of the waterway is decreased, resulting in increased velocity of steam, and, as the river rises these velocities are greatly accelerated, and when drift begins to lodge against the dike, faster restricting the water area, failure of the dike is altogether too frequent to consider any at the present time a success, due chiefly to scour, which I overcome by the employment of my improved form of revetment which is mainly the provision of means for establishing a foundation which will prevent any possible chance of scour of the lower bank or river bed.

The many advantages of the herein described invention will readily suggest themselves to those skilled in the art to which it appertains.

I do not wish to be understood as limiting myself to the exact details of construction and arrangement of parts thereof as herein described, but desire to have it clearly understood that the revetment shown in the drawings is merely illustrative, as it is manifest that minor variations and modifications may be made in the structure without departing from the spirit and scope of my invention and the terms of the appended claims, hence I wish it to be clearly understood that I reserve the right to make any such changes, or modifications as may fairly fall within the scope of the appended claims when fairly construed.

What I claim is:

1. A revetment composed of a lower bank coating layer of quarry spalls graded from fine to the largest fragments to provide a base layer free from voids, a woven willow mattress having deep pockets therein laid upon the lower bank coating, ballast material filling the pockets of the mattress to cause the mattress and ballast to form close contact with the lower bank coating to act as a proof against scour and a coating of rock material spread over the top surface of the mattress substantially free from voids.

2. A revetment composed of a lower bank foundation of graded quarry spalls to free the foundation from voids, a woven willow foot mattress covering having pockets therein for the foundation, a crushed rock ballast carried by the pockets of the mattress to free the mattress of voids and establish close

contact with the lower bank foundation and a covering of crushed rock for said mattress.

3. A revetment composed of a lower bank foundation of graded quarry spalls to free the foundation from voids, a woven willow foot mattress covering having pockets therein for said foundation, a crushed rock ballast carried by the pockets of the mattress to free the mattress of voids and establish close contact with the lower bank foundation, longitudinal and transverse mattress strengthening strands engaging the lower face of the mattress and extending above the upper face of the mattress at the intersections of the strands to form inverted U-shaped bites, toggle levers passing through and engaging the bites for twisting the bites and bring the toggles into engagement with the top face of the mattress to act as spaced baffles and a covering of suitable rock material spread over the top surface of the mattress and held against displacement by means of the spaced toggles.
4. A revetment comprising a mat composed of woven willow members to form deep pockets, longitudinal and transverse metallic strands engaging the lower face of the mattress, upright inverted U-shaped bites formed at the intersection of the longitudinal and transverse metallic strands, wooden toggles engaging the bites and held in position by twisting the bites, means for fastening the ends of toggles to the members of the mattress so as to form spaced baffles upon the upper face of the mattress, rock ballast filling the pockets of the mattress to eliminate voids therein, a voidless quarry spall foundation spread upon the lower bank of the river bed upon which the mattress is seated and to form close contact therewith to prevent scour, and a covering of quarry spalls spread upon the top surface of the mattress and held from casual displacement by the toggles aforesaid.
5. A revetment for shore and dike protection composed of a layer of graded quarry spalls spread upon the lower bank of a river bed, a woven willow mattress having deep pockets therein, strengthening means for said mattress, crushed stone ballast filling the pockets of said mattress to establish close contact with the lower bank foundation when laid thereupon to avoid scour, a top coating of crushed stone spread upon said

mattress and its ballast filling and means to prevent casual displacement of the top coating deposited upon the mattress.

6. A revetment for shore protection consisting of graded quarry spall foundation free from voids, a mattress provided with deep pockets laid upon said spall foundation, ballast filling the pockets of said mattress to free it of voids and cause close contact thereof with the spall foundation to prevent scour, a graded quarry spall top coating for said mattress, and means to prevent casual displacement of said top coating.

7. A revetment comprising a rock material base, a combined woven willow and rock material body laid upon said base and a rock material coating for said combined woven willow and rock material body.

8. A revetment comprising a graded quarry spall base, a layer of woven willows having pockets therein, rock material carried by the pockets of said layer of woven willows to act as a ballast therefor, and a top coating of rock material, the several layers of materials acting as a revetment body to eliminate scour of the river bed covered therewith.

9. A revetment for shore and dike protection comprising a base layer of ballast material, a reticulation of willows to form pockets laid upon the base layer of ballast material, graded quarry spalls intermingled with the reticulation of willows for filling the pockets of said reticulation of willows, means for strengthening the reticulation of willows, spaced toggles fixed to engage the upper surface of said reticulation of willows and a face layer of ballast material for said reticulation of willows.

10. A revetment for shore and dike protection consisting of a reticulation of willows interwoven to form a mat provided with a multiplicity of miscellaneous pockets adapted to be laid upon the shore and river bed, ballast filling for the pockets of said reticulations of willows, longitudinal and transverse strengthening means for said mat, spaced toggles connected to said strengthening means in such a manner as to engage the upper surface of the mat and a face layer of ballast material for said mat.

In testimony whereof, I have hereunto signed my name to the specification.

EDWARD JONES.
